[57] **CLAIM**

The ornamental design for an electric grass trimmer, as shown and described.

DESCRIPTION

FIG. 1 is a perspective view of an electric grass trimmer showing my new design;

FIG. 2 is a side view of the grip portion thereof, shown broken away for ease of illustration, the opposite side being a mirror image;

FIG. 3 is a top view of the grip portion thereof;

FIG. 4 is a bottom view of the grip portion thereof;

FIG. 5 is a front view of the grip portion thereof;

FIG. 6 is a rear view of the grip portion thereof;

FIG. 7 is a top plan view of the bottom portion thereof, shown broken away for ease of illustration;

FIG. 8 is a front view of the bottom portion thereof;

FIG. 9 is a left view of the bottom portion thereof;

FIG. 10 is a bottom view of the bottom portion thereof;

FIG. 11 is a rear view of the bottom portion thereof;

FIG. 12 is a right side view of the bottom portion thereof;

FIG. 13 is a front view of the secondary handle thereof, shown broken away for ease of illustration;

FIG. 14 is a side view of the secondary handle thereof;

FIG. 15 is a rear view of the secondary handle thereof;

FIG. 16 is a top view of the secondary handle thereof; and,

FIG. 17 is a bottom view of the secondary handle thereof.
